CLAIM

The ornamental design for a display panel portion with an animated computer icon, substantially as shown and described.

DESCRIPTION

FIG. 1 is a first image in a sequence for the display panel portion with an animated computer icon.

FIG. 2 is second image in the sequence thereof.

FIG. 3 is a third image in the sequence thereof.

FIG. 4 is a fourth image in the sequence thereof.

FIG. 5 is a fifth image in the sequence thereof.

FIG. 6 is a sixth image in the sequence thereof.

FIG. 7 is a seventh image in the sequence thereof.

FIG. 8 is an eighth image in the sequence thereof; and,

FIG. 9 is a ninth image in the sequence thereof.

The appearance of the transitional image sequentially transitions between the images shown in FIGS. 1-9. The process or period in which one image transitions to another image forms no part of the claimed design.

The broken lines showing a portion of a display panel and portions of the animated computer icon in FIGS. 1-9 form no part of the claimed design.
